UNITED STATES PATENT OFFICE.

JOSEPH P. ELLACOTT, OF CHICAGO, ILLINOIS, ASSIGNOR TO UNION BRASS MANUFACTURING COMPANY, OF SAME PLACE.

STARCHING-MACHINE.

SPECIFICATION forming part of Letters Patent No. 284,119, dated November 9, 1880.

Application filed March 15, 1880. (No model.)

To all whom it may concern:

Be it known that I, JOSEPH P. ELLACOTT, of Chicago, in the county of Cook and State of Illinois, have invented certain new and useful 5 Improvements in Starching-Machines, which are fully described in the following specification, reference being had to the accompanying drawings, in which—

Figure 1 represents a front elevation of a 10 machine embodying my improvements; and Fig. 2, a vertical section of the same, taken on the line *x x*, Fig. 1.

My invention relates to machines for starching clothes, being especially designed for use 15 in laundries; and the object of my present improvements is to prevent the starch from being cooled by the surplus which is expressed by the rollers, and to keep it always at the proper temperature, and also to provide means 20 for readily operating the starching-rollers.

The invention consists in the special construction and arrangement of the steam-pipe, in connection with the vat or tub, and mechanism for compressing the starched fabric 25 over the tub.

It also consists in the special combination of the vat or tub, steam-pipe, and compressing-rollers.

The construction and operation of a machine 30 embodying my invention will be hereinafter fully described, and the special improvements definitely pointed out in the claims.

In the drawings, A represents a metallic frame, consisting substantially of standards *a* 35 at each end, constructed with suitable legs and joined together by cross bars or braces, as may be required, to give the structure strength. The upper portion of these standards is closed, and between them is arranged a plate of sheet 40 metal, *b*, in semicircular form, which is secured to the standards in any suitable manner, thereby forming a vat or tub, B, which constitutes the receptacle for the liquid starch. Near the bottom, and at the rear side of this vat, is arranged a steam-pipe, C, running the entire 45 length of the vat, and having perforations *c* in its under side and a little in front of the center, as shown in Fig. 2 of the drawings. This pipe passes out through one of the standards, 50 and is supplied with steam from the feed-pipe

c', which should be provided with a cock for shutting off and letting on steam at will.

A roller, D, is mounted in the upper part of the standards, above and just a little in rear of the steam-pipe C. The shaft *d*, to which this roller is secured, is provided with suitable 55 bearings on the standards, on which it turns, and on one end, outside of the standards, a driving-wheel, E, is loosely mounted, which is connected with the shaft, at pleasure, by means 60 of an ordinary sliding clutch, F, operated by a lever, *f*.

A second roller, G, is mounted in the upper ends of arms H, which are just outside of the upper portion of the standards, the shaft *g* of 65 the roller being arranged to turn freely in the upper ends of these arms. The arms are fastened at their lower ends to a rock-shaft, I, mounted in the standards underneath the vat, so that by oscillating this shaft the roller G 70 will be swung back and forth over the top of the vat or tub.

A crank-arm, *i*, is fastened to the rock-shaft I, and is arranged to project horizontally in rear thereof. A spiral spring, J, is attached 75 to the outer end of this crank-arm, and, extending upward, is fastened at its upper end to some portion of the frame. Obviously this spring will operate to hold the crank-arm up, thereby keeping the roller G thrown forward 80 to the front of the machine, in the position shown in full lines in Fig. 2 of the drawings.

A treadle, K, is arranged below the tub, being pivoted at its rear end to one of the transverse rods of the frame, and extending in front 85 within easy reach of the attendant. This treadle is connected by a rod, *k*, to the outer end of the crank-arm *i*, so that whenever the treadle is depressed, as shown in dotted lines in Fig. 2 of the drawings, the roller G will be 90 swung over the top of the tub toward the rear of the machine until it is brought into contact with the roller D, as shown in dotted lines in said Fig. 2.

The two rollers D and G are elastic, rubber 95 rollers being preferable, and the roller D is preferably slightly larger in diameter than the roller G. The roller D is rotated outward in the direction of the arrow in Fig. 2 of the drawings by means of the driving-wheel E, and 100

whenever the roller G is brought into contact with the roller D, or with anything between the two rollers, a corresponding outward rotation will be communicated to the said roller G, as also indicated by an arrow in the same figure.

The table L is attached to the frame-work of the machine in rear of the tub and slightly above the rollers, and a narrow strip or table, L, is arranged at the front of the machine, which 10 partially covers the roller G when in a state of rest.

The tub is provided with a discharge-cock, M, at its bottom, by means of which it may be emptied whenever desired.

15 The operation of this machine is as follows: The tub is partially filled with the prepared starch and steam let on sufficient to keep the starch at about a boiling temperature. The rollers being separated, as shown in full lines 20 in Fig. 2 of the drawings, the articles to be starched are immersed in the liquid. Then with a hook the attendant seizes one of the articles and lifts it to a point between the rollers, when the roller G is thrown to the rear by 25 depressing the treadle until the article of clothing is pinched between the two rollers. The roller D in the meantime having been set in motion, it is evident that the clothing will be carried upward between the two rollers, and, 30 the roller G being held up with sufficient pressure against the clothing, the starch is evenly distributed throughout the fabric and all surplus expressed. The starched garment is carried upward and backward upon the table L. 35 The starch expressed by the action of the rollers will, of course, be cooled, and, if it fell back into the tub in front of the rollers, would naturally be the first used subsequently, and thus cold starch would be applied to the clothing 40 instead of hot. Now, from the arrangement of the steam-pipe and rollers, the cool starch, when expressed by the rollers, falls a little in rear of the steam-pipe, and by reason of the special arrangement of the inlet-openings in the steam- 45 pipe a slight current is produced by the injecting steam downward and forward from the pipe, owing to the inclination or curvature of the bottom of the tub. This action will cause

the cool starch falling from the rollers to be carried downward at the rear of the tub, behind and underneath the steam-pipe, where it is brought into immediate contact with the steam and thereby reheated, so that the entire body of starch will be kept constantly heated to the required degree.

55 It will be noticed that with the mechanism above described no force is required to pull the articles through the rollers, but the action is entirely automatic when the vibrating roller is thrown up against the revolving roller, and 60 the certainty of the action is somewhat improved by making the driving-roller slightly larger than the vibrating roller. The spring will, at all times, tend to separate the rollers whenever released from the action of the treadle. The arrangement of the steam-pipe tends 65 to keep up a constant motion in the starch body to thoroughly mix and heat the latter.

The parts of this machine may be changed in construction and arrangement, obviously, 70 without materially changing the operation whereby the useful results are obtained.

Having thus described my invention, what I claim as new, and desire to secure by Letters Patent, is—

75 1. In a starching-machine, the vat or tub and a steam-pipe, C, arranged at the bottom and near one side of the tub, and provided with inlet-openings in its under side and toward the farther side of the tub, in combination with mechanism for compressing the starched fabric over the tub at the side nearest to the steam-pipe, substantially as and for the purpose set forth.

2. The tub B, having an inclined or curved 80 bottom, in combination with the steam-pipe C, arranged in the bottom at one side of the tub, and provided with inlet-openings on its under side and a little inside the center thereof, and the elastic rollers D G, all arranged and operating substantially as described.

JOSEPH P. ELLACOTT.
